UNITED STATES PATENT OFFICE.

ALFRED DE MEURISSE, OF PHILADELPHIA, PENNSYLVANIA.

GAME APPARATUS.

941,793.

Specification of Letters Patent. Patented Nov. 30, 1909.

Application filed January 27, 1909. Serial No. 474,373.

To all whom it may concern:

Be it known that I, ALFRED DE MEURISSE, a citizen of the United States, and resident of the city and county of Philadelphia, 5 State of Pennsylvania, have invented certain new and useful Improvements in Game Apparatus, of which the following is a full, clear, and exact description, reference being had to the accompanying drawings, forming 10 a part of this specification.

This invention relates to the bowling alley type of game apparatus, wherein are employed a suitable bed or table over which balls may be rolled by the players, and a 15 series of pins arranged to be knocked down by the action of the balls under the control of the players.

The object of my invention, as generally stated, is to provide, in a game apparatus 20 of this type, a novel and improved construction and organization of parts, first: whereby the pins may rest normally in an upright position from which they may be easily knocked down by the action of a ball; secondly: whereby the pins may be readily elevated to the upright position after they have been knocked down; thirdly: whereby the action of one pin, in falling from its upright to its knocked-down position, will 25 carry with it one or more additional pins; fourthly: whereby, by the adjustment of certain parts, various changes may be effected in the operation of certain pins in carrying with them certain other pins in 30 moving from their upright to their knocked-down positions; and fifthly: whereby, by the adjustment of certain parts, each pin may be separately knocked down without 35 disturbing the positions of the other pins.

Having this general object in view, the invention consists in the novel construction and combination of parts which will be hereinafter fully described and particularly claimed.

In the drawings:—Figure 1 is a perspective view of my improved game apparatus. Fig. 2 is a plan view of the end of the table carrying the pins and the other parts connected thereto. Fig. 3 is a side elevation of 45 the parts shown in Fig. 2. Fig. 4 is a vertical section showing one of the pins and its 50 operating plunger. Fig. 5 is a rear view of the parts shown in Figs. 2 and 3. Fig. 6 is a horizontal section through parts of the table and the cushion pads, showing the 55 plungers for knocking down the pins, and adjuncts. Fig. 7 is a vertical section on line 7—7 of Fig. 5.

8 designates a suitable elongated bed or table, over which a ball 9 is adapted to be 60 rolled by the players. The table 8 is preferably arranged on an incline, as shown, and it is provided with upwardly-extending side walls 10 to prevent the ball or balls 9 from rolling laterally from the table. The lower 65 end of the table is provided with a wall 11, preferably a cushion strap positioned to receive the ball or balls 9 when they roll downwardly upon the table 8 to the lower end thereof. The table 8 may be of any desired 70 length, and it may be supported in any desirable manner. In the present instance I have shown the table provided with legs 12 which support it a suitable distance above the floor. Formed on or secured to the upper 75 end of the table is an end board 13 which extends between the sides 10, and which also extends above the top of the table 8.

Extending upwardly from the end board 13 are pins 14, seven in number, arranged in 80 a row transversely of the table 8. Each pin comprises a body portion 15, shaped to simulate a pin of the well-known "ten-pin" game, and a downwardly extending arm 16 secured to the body 15. The lower end of 85 the arm 16 of each pin 14 is pivoted to a rod 17 which extends through bearings 18 on the board 13. Each pin 14 extends forwardly of its pivot and rests normally against a head 19 on the rearward end of a 90 plunger 20 which extends freely through an opening in the board 13 parallel to the face of the table 8. The forward end of each plunger 20 is provided with a head 21, and the distance between the heads 19 and 21 of 95 each plunger 20 is greater than the thickness of the board 13, thus permitting free longitudinal movement of the plungers 20 within their openings in the board 13. When a pin 14 rests against the head 19 of 100 a plunger 20, the head 19 is pressed against the rearward face of the board 13 and the

head 21 is projected forwardly of the forward face of the board 13. It will thus be seen that if the plunger 20 be projected rearwardly by the impact of the ball 9 against 5 its head 21, the head 19 of the plunger will move the opposing pin 14 rearwardly on its pivot, and the action of the plunger 20, together with the weight of the pin 14, will cause the pin to move from its normal or 10 upright position shown by full lines in Fig. 3 to a knocked-down position shown by dot-and-dash lines therein.

When each pin 14 is moved to the knocked-down position shown by dot-and-dash lines 15 in Fig. 3, it falls upon and is supported by a cushion strap 22, which extends parallel to the row of pins 14, and has its ends secured to projections on a frame 23. The frame 23 is hinged, as at 24, to the board 20 13. The part of the frame 23 extending rearwardly from the hinge 24 is heavier than the part of the frame 23 extending forwardly from said hinge; therefore the frame 23 rests normally in the horizontal 25 position shown by full lines in Fig. 3, the forward portion of the frame 23 abutting against the bottom of the board 13 and limiting the downward movement of the main body of the frame. By moving the 30 frame 23 from the position shown by full lines in Fig. 3 to the position shown by dot-and-dash lines therein, any pins that have been previously knocked down and are resting upon the strap 22, may be elevated or 35 returned to the normal upright position in which they rest against the heads 19 of the plungers 20, and at the same time the plungers 20 of the knocked down pins are projected forwardly through their openings in 40 the board 13 by the engagement of the pins 14 therewith.

As a suitable means for raising the frame 23 to return to normal position the knocked-down pins 14, I provide a hand lever 25, 45 arranged at the forward or lower end of the table 8. This lever 25 is pivoted, as at 26, to one leg 12 of the table, and connected to the lever 25 is one end of a cord or wire 27, which extends over pulleys 28 on the 50 under side of the table 8; thence to and around a pulley 29 which is supported by a bracket 30 on transverse bars 31 extending between the legs 12 at the upper end of the table 8; and thence to an arm 32 which 55 extends forwardly from the frame 23 and to which the other end of the cord or wire 27 is secured. The position of the pulley 29 with relation to the arm 32 is such that when the lever 25 is moved outwardly from 60 the table 8 it will draw upon the wire 27 and pull down the arm 32, thus raising the frame 23 from the position shown by full lines in Fig. 3 to the position shown by dot-and-dash lines therein, and at the same

time raise the knocked-down pins from the 65 position shown by dot-and-dash lines in Fig. 3 to the normal position shown by full lines therein. After the knocked-down pins have been elevated to the normal position just described, and the lever 25 is released, the 70 frame 23 will, by its own weight, return to its normal horizontal position shown by full lines in the drawings, and at the same time return the lever 25 to its normal or operative position for a succeeding operation. 75

Seured to the forward face of the board 13 on each side of each head 21 of each plunger 20, is a cushion pad 33, which may be constructed of any suitable yielding material; and when the plungers are projected forwardly by the pins 14, the heads 21 on the plungers 20 will extend forwardly of the forward faces of the cushion pads 33. It will thus be seen that when the ball 9 80 is rolled over the top of the table 8 toward the heads 21 of the plungers 20, the ball 9 will strike a pad 33 and be cushioned thereby if the ball does not strike a head 21 of one of the plungers 20. Each plunger 20 is provided with a collar 34 of yielding material surrounding the same between its head 21 and the forward face of the board 13, which forms a stop to act against the forward face of the board 13 and limit the 85 rearward movement of the plunger 20 when it is projected rearwardly by the action of the ball 9, the impact of the ball against the head 21 being cushioned by the action of the yielding collar 34. 90

The pins 14 are numbered "1", "2", "3", "4", "5", "6" and "7", — "7" being the center pin, "5", "3" and "1", respectively, being the three pins on one side of the center pin, and "6", "4", and "2", 105 respectively, being the three pins on the other side of the center pin, as shown. The vertical arm 16 of each of the pins 3 and 4 is provided with a horizontal bar 35 which extends beyond the sides of its arm 16. The 110 outer ends of the bar 35 carried by the pin 3 are in line with and inwardly of brackets 36 extending from the arms 16 of the pins 1 and 5, whereby, when the pin 3 is knocked down, its bar 35 will strike against the 115 brackets 36 and thereby knock down the pins 1 and 5 with the pin 3. The outer ends of the bar 35 carried by the pin 4 are in line with and inwardly of brackets 37 extending from the arms 16 of the pins 2 120 and 6, whereby, when the pin 4 is knocked down, its bar 35 will strike against the brackets 37 and thereby knock down the pins 2 and 6 with the pin 4. These bars 35 are each detachably secured to the arms 16, 125 each bar 35 being inserted into a bracket 38 on the arm 16 and held therein by a pin 39 carried by a spring 40 on the arm 16 and

extending through the bracket 38 and into an opening in the bar 35.

From this construction it will be seen that by pressing the spring 40 outwardly, the 5 pin 39 may be withdrawn from the opening in the bar 35, thereby freeing the bar and permitting its detachment from the arm 16.

When the bars 35 are in place upon the 10 arms 16 of the pins 3 and 4, the pins 1 and 5 will be knocked down by the knocking down of the pin 3, or the pins 1 and 5 may be knocked down independently of each other and of the pin 3; and the pins 2 and 6 will be knocked down by the knocking down of 15 the pin 4, or the pins 2 and 6 may be knocked down independently of each other and of the pin 4.

Arranged directly in the rear of the arm 16 of the center pin 7 is an arm 41 which 20 extends upwardly from a bar 42 which is hinged to the frame 23 as at 43, and which is held normally upright by the action of suitable springs 45 surrounding the pins of the hinges 43. The bar 42 is connected to 25 the bars 35 by chains 46; and the position of the arm 41 with relation to the arm 16 of the center pin 7 is such that when the center pin is knocked down it will engage the arm 41 and move it and therewith the bar 42 30 rearwardly on the hinges 43. The rearward movement of the bar 42 causes the chains 46 to pull rearwardly the bars 35 and therewith the pins 1, 3, and 5, and 2, 4 and 6, thus bringing to the knocked-down position all the pins by the knocking down of 35 the center pin 7.

The arm 41 is detachably secured to the bar 42 by a set-screw 47 extending through the arm 41 and into the bar 42. By removing the set screw 47 the arm 41 may be readily detached from the bar 42.

By detachably securing the bars 35 to the arms 16 of the pins 3 and 4, and by detachably securing the arm 41 to the bar 42, I am 45 enabled to make the following combinations:—First: When the arm 41 is secured to the bar 42 and the bars 35 are secured to the arms 16 of the pins 3 and 4, the pins 1, 2, 5, and 6 may be knocked down independently of each other and of the pins 3, 4, and 7; the knocking down of the pin 3 will cause the pins 1 and 5 to be knocked down; the knocking down of the pin 4 will cause the pins 2 and 6 to be knocked down; and 50 the knocking down of the center pin 7 will cause all the pins to be knocked down.

Secondly: By removing the arm 41 from the bar 42, the pins 1, 2, 5, 6, and 7 may be knocked down independently of each other 55 and of the pins 3 and 4; the knocking down of the pin 3 will cause the pins 1 and 5 to be knocked down; and the knocking down of the pin 4 will cause the pins 2 and 6 to be knocked down. Thirdly: By detaching the

bars 35 from the arms 16 of the two pins 3 65 and 4, all the pins may be knocked down independently of each other.

In order to prevent the interference of the arm 41 and bar 42 with the other parts of the apparatus when the frame 23 is raised to 70 return the pins 14 to their upright or normal position, I attach one end of a chain 48 to a pin 49 projecting from the bar 42, and the other end of the chain 48 to the bracket 30. It will thus be seen that when the frame 23 75 is raised to raise the pins 14 as previously explained, the chain 48 will draw the bar 42 and therewith the arm 41 outwardly against the action of the springs 45.

The upper ends of the pins 3, 4 and 7 are 80 provided with suitable weights to enable them to more effectually carry with them when they are knocked down other pins of the device, as hereinbefore explained. Arranged above the pins 14 is a signboard 50, 85 which is supported by standards 51 rising from the sides of the table 8. On this signboard 50 is indicated the value of each pin, the value of the center or king pin being four, and the value of each additional pin 90 being one, thus indicating that, in playing the game, four should be scored if the center pin is knocked down, and one should be scored for each of the other pins. Extending upwardly from each side of the upper end of 95 the table 8 is a suitable guard screen 52, which prevents the balls from leaving the table in their rebound after striking either a plunger for one of the pins or a cushion pad.

In playing the game, the players stand at 100 the lower end of the table 8 and roll the balls over the table with a view of striking the head 21 of one of the plungers 20 and knocking down one of the pins 14.

The game may be played in many different ways. When the arm 41 is in place upon the bar 42 and the bars 35 are in place upon the pins 3 and 4, the game may be played and scores made very similar to the well 110 known ten-pin game in which a “strike” and a “spare” can be made. That is to say, if two balls are allowed a player and with the first ball the center or king pin is knocked down, thereby carrying with it all 115 the other pins, a “strike” is made; and if the strike is not made with the first ball and with the second ball the player knocks down the pins not knocked down with the first ball, a “spare” is made. Thus counts and 120 scores can be made in accordance with the rules for counting and scoring in the common and well known game of bowling or ten-pins. By removing the bars 35 from the pins 3 and 4, a “call pin” game may be 125 played; that is to say, each player, before rolling the ball, will be required to name the pin that is intended to be knocked down,

and should any pin other than the pin called be knocked down, the player will not score.

It will of course be perfectly obvious that the manner of playing the game and scoring is capable of wide variation; and by detaching one or both of the bars 35 or the arm 41 different combinations hereinbefore referred to may be made.

I claim:—

10 1. The combination of a table and pins extending above the table and having their lower ends pivotally connected thereto, said pins resting normally in a position extending angularly forward of their pivots, and being rearwardly movable to a knocked down position by a forward impact of the ball.

20 2. The combination of a table and pins extending above the table and having their lower ends pivotally connected thereto, said pins resting normally in a vertically inclined position extending forwardly of their pivots and being rearwardly movable to a knocked down position by a forward impact of the ball, resilient means to receive said pins in the knocked down position, and means for raising said pins to normal position.

30 3. The combination of a table and a series of pins extending above the table, a transversely-disposed board to which said pins near their lower ends are hingedly connected, said pins resting normally in a vertically inclined position extending forwardly of their pivots, a series of independent plungers 35 for each pin passing through apertures in said board, and adapted to be actuated in a rearward direction by an impact of the ball delivered in a direction forward of the pin, and to be restored to normal operative position by restoring the pin to normal position.

40 4. The combination of a table and pins extending above the table and having their lower ends pivotally connected thereto, said pins resting normally in a position extending forwardly of their pivots and being rearwardly movable to a knocked down position, independently movable plungers arranged to act upon said pins and to be acted upon by a ball rolled over said table, and cushion pads 50 adjacent said plungers.

55 5. The combination of a table having an end wall projecting above the top thereof, a plunger extending through an opening in the end wall and having a head on each end thereof, the distance between the heads of the plunger being greater than the thickness of the wall through which the plunger extends, and a movable pin extending above the table and resting normally against the 60 rearward end of the plunger.

65 6. The combination of a table having an end wall projecting above the top thereof, a plunger extending through an opening in the end wall and having a head on each end

thereof, the distance between the heads of 65 the plunger being greater than the thickness of the wall through which the plunger extends, a pin resting normally in an upright position against the rearward end of the plunger and movable from the upright to a 70 knocked down position, and means for elevating said pin from the knocked down to the upright position.

7. The combination of a table having an end wall projecting above the top thereof, 75 a plunger extending through an opening in the end wall and having a head on each end thereof, the distance between the heads of the plunger being greater than the thickness of the wall through which the plunger extends, a pin resting normally in an upright position against the rearward end of the plunger and movable from the upright to a knocked down position, a pivoted frame positioned to engage and elevate said pin 80 from the knocked down to the upright position, and means for operating said frame.

8. The combination of a table having an end wall projecting above the top thereof, a plunger extending through an opening in 90 the end wall and having a head on each end thereof, the distance between the heads of the plunger being greater than the thickness of the wall through which the plunger extends, a movable pin extending above the 95 table and resting normally against the rearward end of the plunger, and cushion pads on the forward face of said wall laterally of said plunger.

9. The combination of a table, a series of 100 pins extending above the table in a vertically-inclined position, means to pivotally support the lower ends of the pins in such inclined position, independent means for knocking down each of said pins by an impact blow delivered against the pin on the side of its smaller angle of inclination, and detachable means actuated by a knock down of the center pin in the series for knocking down the next contiguous pin successively 110 in the entire series.

10. The combination of a table, pins resting normally in an upright position and positioned to be knocked down by the action of a ball rolled over the table, a bar detachably secured to one pin, and a bracket projecting from another pin and positioned to be engaged by said bar when the pin carrying the bar is knocked down.

11. The combination of a table, pins resting normally in an upright position and positioned to be knocked down by the action of a ball rolled over the table, a hinged bar, an arm projecting from said bar and positioned to be engaged by a pin when it is 125 knocked down and rock said bar on its hinge, and means operated by the rocking of said bar for knocking down another pin.

12. The combination of a table, pins resting normally in an upright position and positioned to be knocked down by the action of a ball rolled over the table, a hinged bar,
5 an arm projecting from said bar and positioned to be engaged by a pin when it is knocked down and rock said bar on its hinge, means operated by the rocking of said bar for knocking down another pin, and
10 means operated by the knocking down of

the last named pin for knocking down another pin.

In testimony whereof, I have hereunto affixed my signature this 25th day of January A. D. 1909.

ALFRED DE MEURISSE.
